UNITED STATES PATENT OFFICE

HERMAN L. HARTENSTEIN, OF CHICAGO, ILLINOIS

APPARATUS FOR COOLING INTERNAL COMBUSTION ENGINES

Application filed October 18, 1926. Serial No. 142,193.

This invention relates to apparatus for cooling internal combustion engines, and particularly such engines when used on motor driven vehicles.

As is generally well known, it is common practice to cool internal combustion engines—particularly the cylinders thereof—by means of jackets which enclose the engine cylinders, through which a circulation of relatively cool

fluid is maintained.

In the case of stationary engines, cold water is commonly used, it being obtained from a suitable source of supply, used but once, and permitted to run to waste after being used, thus necessitating the use of large quantities of the cooling medium.

In the case of engines used for propelling motor driven vehicles, it is obviously impossible to cool the engine by means of water obtained from a source outside of the vehicle, and when used for this purpose, the practice is to cool the engines by means of a quantity of liquid carried by the vehicle, which is recirculated through the jackets of the engine

25 cylinders and is maintained at a relatively low temperature by circulating it through a cooling apparatus mounted on the vehicle, usually a radiator which has suitable circulating pipe connections with the jackets of the engine cylinders.

As is generally well known, also, where water is the cooling medium—which it is in a very large percentage of cases—there is danger of its freezing in severe weather in case the engine is permitted to stand for any considerable length of time, thus preventing circulation of the cooling medium and in many cases resulting in rupture of the radiator cells or tubes, thus requiring that they be replaced.

40 This objectionable feature is usually remedied by mixing with the cooling medium a quantity of what is usually known and referred to as an anti-freezing mixture or solution, which has the characteristic of imparting to the entire body of the cooling medium a freezing point materially lower than that of water or other cooling medium used.

45 The solution generally used consists of denatured alcohol and water, the proportions of which vary with the temperature against

which protection is desired, an approximate range being from 12 parts of alcohol and 68 parts of water for temperatures approximating 18 degrees F. above zero, to 56 parts of alcohol and 24 parts of water for temperatures approximating 57 degrees F. below zero.

There are, however, many different anti-freezing mixtures, the freezing points varying to a greater or less extent and the relative quantities of water and solution to be used will, of course, vary accordingly. The correct proportions for different freezing mixtures is, however, usually specified in available formulae and need not be considered in detail.

While anti-freezing mixtures are of great value in the respect that they prevent freezing of the cooling medium, they also possess certain inherent objectionable characteristics, a principal one of which is that they are more volatile than the water with which they are commonly used and, therefore, appreciably reduce the boiling point of the cooling medium.

It is recognized that internal combustion engines operate most efficiently at temperatures of from 170 to 180 degrees F., which is materially below the boiling point of water but appreciably above that of the anti-freezing solution. The same is also true of other anti-freezing solutions containing alcohol. It therefore follows that, even at efficient operating temperatures, the use of cooling media containing anti-freezing solution will result in a rapid conversion of the alcoholic content of the cooling media and also of a relatively small portion of the water into vapor and steam, which pass out through the overflow pipe and are lost, and also very frequently the boiling or ebullition is so violent that much of the liquid solution itself is blown out of the overflow pipe. Obviously this condition will be aggravated at higher temperatures. Such losses naturally result in rapidly diminishing both the quantity and quality of the cooling medium to such an extent that its freezing point is correspondingly raised and its cooling capacity is decreased to the extent of such losses, which must be replenished by additional solution in order to

maintain both its anti-freezing and cooling qualities at the proper standard, and for the replenishment of such losses it is customary to add a mixture containing three parts of 5 alcohol and one part of water; and if the proper proportion of anti-freezing solution is not restored or maintained, this would tend to cause freezing of the radiator—if there is too little of the anti-freezing solution—or 10 overheating and improper operation of the engine if there is too much of the anti-freezing solution.

The object of the present invention is to provide means, in association with the usual 15 radiators of internal combustion engines used for propelling motor driven vehicles, constructed and arranged to prevent loss of the ingredients of cooling media used to prevent overheating of internal combustion engines, 20 thereby preventing deterioration of such cooling media, with its attendant injurious effects; and also to prevent the attendant large economic loss resulting therefrom.

Stated generally, I attain the objects of the 25 invention by condensing means installed so as to communicate with what may be designated the high temperature side of the cooling system of the engine, that is between the discharge from the jackets of the engine cylinders, 30 constructed and arranged to receive vaporized cooling medium generated in the jackets as it passes to the radiator, and to condense practically all of the vaporized cooling medium and to return it to the cooling system in liquid form.

In what I now consider to be the preferable embodiment of my invention, the improved condenser consists of a coil made of suitable thin metal tubing, preferably copper, 40 supported upon a suitable base portion which forms a cap or closure for the filling opening of the radiator, the lower end of said body portion being screw-threaded to engage the same. Preferably, also, said coil comprises a return section which leads back into 45 the radiator in register with and which terminates in close proximity to the end of the overflow pipe of the radiator (not shown) forming, in effect, a closure or liquid seal therefor which will prevent vaporized cooling medium from entering the same and thus 50 running to waste.

To render the condenser more sightly in appearance and also to protect the coil from 55 damage or breakage by being struck, the condenser also preferably comprises a casing which encloses said coil, said casing preferably being skeletoned or cut out to permit free access of the air to the coil.

60 The invention also comprises the various other features and details of construction hereinafter described and claimed.

In the accompanying drawings, in which this invention is fully illustrated,

65 Figure 1 is a diagrammatic view illustrat-

ing apparatus for cooling internal combustion engines embodying this invention and improvements, exemplifying the same as applied in use for cooling the cylinders of an engine of an automobile or other motor driven vehicle.

70 Figure 2 is a front view of a condenser embodying this invention and improvements, shown as applied in use to the radiator of a motor driven vehicle.

75 Figure 3 is a view substantially similar to Fig. 2, on an enlarged scale, parts thereof being shown in section on the line 3—3 of Fig. 4.

Figure 7 is an enlarged vertical sectional view of Fig. 6.

Figure 8 is a sectional view on line 8—8, Fig. 6.

89 Figure 9 is a vertical sectional view illustrating another modification.

Figure 10 is a view partly in side elevation, partly in section of another form of the invention.

93 Figure 11 is a view similar to Fig. 10 of still another form of the invention.

In the accompanying drawings I have, for purposes of clear and definite illustration, shown a cooling apparatus embodying my invention and improvements as applied in use for cooling the cylinders of internal combustion engines used for propelling an automobile or other motor driven vehicle.

Describing the invention with particular reference to Figs. 1 to 5 of the drawings, A, Fig. 1, indicates, diagrammatically, the engine of a motor vehicle, B, the radiator for cooling the water which circulates through the jackets of the engine cylinders, a, a' pipes which connect the extreme cylinder jackets with the upper and lower ends of the radiator B, and C indicates a condenser embodying this invention and improvements supported in the filling opening of the radiator which communicates with the vapor space therein.

98 Excepting as regards the condenser C, all of the foregoing parts may be of any usual or approved construction.

Referring particularly to Figs. 2 to 5, inclusive, the condenser C consists essentially of a coil c made of tubing which is a good conductor of heat, preferably copper, supported with the open lower end of the tube forming said coil in communication with the vapor space in the upper part of the radiator B, and which condenser projects above the radiator in position to be exposed to air currents produced either by the wind or by movement of the vehicle.

As shown, the coil *c* is supported by a base portion, designated as a whole *c'*, said base portion comprising a plate 1 formed through which is a hole 2, in which the lower 5 end of the tube forming the coil *c* is secured. The lower end of the base portion *c'* is threaded to engage in the filling opening 3 of the radiator formed by the thimble 4 on said radiator.

10 For reasons presently apparent, means are provided for adjusting the condenser *C* axially. As shown, this is effected by forming the base portion *c'* in two parts, consisting of the plate 1 and a bushing 5, the lower end 15 of said bushing being screw-threaded directly into the filling opening 3 and the lower end of the plate 1 terminating in a circular projection 6' fitted to turn in a hole 6 formed in the upper end of the bushing 5,

20 the plate 1 and bushing 5 being connected by a nut 7 threaded to the lower end of the circular projection 6' on said plate 1 and which is adapted to bear against an interior shoulder 8 on the bushing 5. In practice, the nut 25 7 is adjusted so that the plate 1 is held in position frictionally, thus permitting the coil *c* and parts directly associated therewith to be turned into desired position. A tight joint can be formed between the parts of said base portion by means of a packing gasket 9 inserted between the nut 7 and the shoulder 8.

The front and back sides of the coil *c* may be flat, thus exposing a greater radiating surface to air currents traversing the condenser than would otherwise be the case, and it is to provide for adjusting said condenser with a flat side in front that the described provision for axial adjustment of the condenser 40 is provided for.

To protect the coil *c* from injury, a casing *c*² may be provided to enclose the coil, the sides of said casing being skeletoned to permit free access of the air to the coil. As 45 shown, said casing *c*² may be provided on all sides with slots 10 the length of which is substantially equal to the height of the coil. Said casing may conveniently be made of sheet metal, as brass or aluminum, and its 50 lower end is fitted to a rabbetted shoulder 11 formed on the base plate 1, and is removably secured in position by means of screws or similar means.

The lower plate 1 forming part of the base 55 portion *c'* of the condenser, is preferably recessed as at 12 to reduce the weight thereof.

With the described construction, it is obvious that steam or vapor from the cooling medium will rise into the vapor space of the 60 radiator and will pass thence upwardly into the coil *c*, where it will be condensed, the pitch of the coil being such that all condensation therein will drain by gravity back into the radiator. To prevent unvaporized liquid 65 particles from being blown upwardly into

the coil *c*, as might occur if the cooling medium were heated to a temperature considerably in excess of its boiling point, which would cause violent ebullition thereof, a baffle 13 may be provided within the recess 70 12 to extend over the open lower end of the coil and at a short distance therefrom, against which baffle the liquid particles will strike, while steam and other light vapors will pass around said baffle into the coil. 75

The coil *c* preferably is made of such length that, at ordinary temperatures the vapors will be condensed before they reach the upper end of said coil.

To permit steam and other light vapors to rise freely into the coil *c*, said coil preferably comprises a pipe section 14 which is reversely bent at the top of the coil and extends downwardly in the space defined by the convolutions of the coil and through an opening 80 formed in the plate 1 of the base portion, the lower end of the pipe preferably registering with the overflow pipe 15 of the radiator. 85

Preferably, also, the lower end of said pipe section 14 is bent as shown at 16 to form a trap in which condensation will collect, thus sealing the lower end of said pipe so that, excepting at very excessive temperatures, steam and vapor will not flow through the coil to pass to waste through the overflow pipe 15. 90 95

Preferably, also, the open lower end of the pipe section 14 extends into such close proximity to the open upper end of the overflow pipe 15 that said overflow pipe will form in effect a continuation of said pipe section 14, 100 thus preventing steam and vapors from entering said overflow pipe directly from the vapor space and being lost.

This invention will also prevent loss of anti-freezing solution by condensing it and returning the condensation to the body of cooling medium, thus maintaining a cooling medium having a substantially constant boiling point and also preventing to a great extent the loss of anti-freezing solution. 105 110

Obviously the condenser and casing may be of any desired shape or configuration.

In order to conveniently supply cooling solution to the radiator and communicating chambers, the casing may be hinged to the 115 base plate, suitable means being provided for securing the hinged section of the condenser in operative position.

Such a construction is shown in Figs. 6 to 8, inclusive, in which *B'* indicates the radiator, 120 *4'* the fill opening thereof, *C'* the condenser, as a whole, *c*³ the base portion of the condenser, comprising a bushing 5' having screw-threaded engagement with the fill opening 3', and a plate 1' hinged thereto at 17, *c*⁴ a coil, 125 shown as circular in form, the lower end of which is secured in the plate 1', *c*⁵ the casing which encloses the coil *c*⁴, provided with slots 10' permitting access of air currents to the coil, and 14' the return section of the coil ex- 130

tending from the upper end thereof downwardly through the plate 1' into register with the overflow pipe of the radiator, not shown.

5 A spring catch 18 secured to the plate 1' engages a shoulder 19 on the bushing 5', to hold the casing in position.

As a further modification of this invention, the return pipe may comprise two branches, 10 one of which is preferably arranged in substantial alignment with the upper section thereof and extends somewhat below the level of the cooling medium in the radiator, and having the lower end thereof contracted, the 15 relation being such that any liquid which may find its way into said return pipe will drain by gravity into the radiator, while, due to the small size of its contracted lower end, very little liquid will be forced into the 20 same by any sudden pressure impulses in the radiator. The other branch or section of said return pipe is off-set as at 14⁴ from the common upper section thereof and is connected laterally into the same, its lower end being 25 arranged in register with the overflow pipe 15 of the radiator and extending into close proximity to the open upper end of said overflow pipe, so that said overflow pipe will form in effect a continuation or extension of said 30 branch return pipe, thus preventing excessive pressures from being generated in the radiator and its connections, due to overheating and violet ebullition of the cooling medium, which would tend to cause flooding of the 35 condenser and possible rupture and other possible damage to the radiator. Obviously, with the construction described, any excess pressure in the radiator will at once be relieved by discharge of a portion of the contents of the radiator—in the form of steam or cooling medium heated to an excessively 40 high temperature—through the condenser to the overflow pipe of the radiator, thereby preventing damage to the radiator and all other 45 objectionable results, excepting the loss of cooling medium, which can readily be replenished.

This modification is shown in Fig. 9 of the drawings, in which C² indicates the condenser as a whole, c⁶ the base portion thereof, comprising the plate 1² and bushing 5² secured in the fill opening 3² of the radiator, c⁷ the coil, the lower end of which is secured in the plate 1², c⁸ the skeletonized casing which 55 encloses the coil, and 14² the return section of the coil, which, comprises two branches 14³ and 14⁴, of which the branch 14³ is arranged substantially in line with the common upper section of said return pipe and extends 60 downwards through the plate 1² below the designed liquid level in the radiator, the lower end of which branch is contracted, as shown at 20^a, the relation being such that liquid will drain by gravity from the common 65 upper section of said return pipe directly into

the radiator. The branch 14⁴ is off-set from the common upper section of said return pipe and extends downwards through the plate 1² with its lower end in register with the open upper end of the overflow pipe 15 of the radiator and into such close proximity thereto that it will form, in effect, a closure therefor adapted to prevent cooling medium from passing directly from the radiator into the overflow pipe and thus to waste.

70 The apparatus thus far has been described as a unit complete in itself, including a base portion adapted to form a closure for the filling opening of the radiator and to replace the usual radiator cap. However, the device 80 may be constructed to form an attachment readily adapted to be attached to the usual radiator cap. Such a construction is illustrated in Figures 10 and 11 of the drawings in which the usual fill cap 20 is employed 85 with the fill opening 4. This cap is provided with an opening 21 which is now usually employed for the attachment of a meter or some ornament, which is adapted to be removed so that the same cap 20 may be employed in connection with this invention.

90 In Figure 10 the coil 22 is connected by its extremities 23 and 24 to a supporting base 25, the latter being provided with a chamber 26 therein with which the ends of the coil have communication. The base 25 is provided with a tubular depending portion 27 which is exteriorly screw threaded as at 28 and is adapted to be passed through the opening 21 in the cap 20 to project therebeyond.

95 Nuts 29 are threaded upon the tubular projection 27 so as to clamp or secure the base 25 to the cap 20.

If desired a gasket or suitable packing 30 may be interposed between the nuts and the inner face of the cap 20 so as to provide a fluid tight joint and thereby prevent the escape of vapor through the cap 20 to the atmosphere.

100 The inlet end 23 of the coil 22 is preferably arranged in alignment with the opening in the tubular portion 27 so that the vapors from the radiator will pass into the coil, and the outlet 24 of the return pipe 31 of the coil is preferably arranged out of alignment with the opening in the projection 27, a baffle plate 32 being preferably provided so as to prevent the vapor from passing directly into the pipe 31.

110 In the form of the invention shown in Figure 11 the ends 33 and 34 of the coil 35 project into a hollow plug like device 36, the latter being preferably provided with a head 37, which rests against the outer face of the cap 20. The body portion of the plug projects through the opening 21 in the cap and nuts 38 are screwed upon the plug to co-operate with the head 37 to clamp the plug to the cap 20. A suitable packing or gasket 115

39 may be provided to form a fluid tight joint.

5 The extremity 40 of the end 34 of the coil is preferably contracted so as to insure the entrance of a greater portion of the vapor into the end 33 of the coil 35.

10 With the forms of the invention shown in Figures 10 and 11 it will be manifest that by removing the ornament or meter which is now employed in devices of this character the present invention may be readily applied and may as readily be removed when desired.

15 Obviously a suitable casing (not shown) may be provided, if desired, for protecting the coil, and the coil may be of any desired length and diameter.

20 While the preferred forms of the invention have been herein shown and described, it is to be understood that various changes may be made in the details of construction and in the combination and arrangement of the several parts, within the scope of the claims, without departing from the spirit of this invention.

25 What is claimed as new is:—

1. In cooling apparatus for internal combustion engines embodying a radiator having a fill opening and a vapor space with which the condenser communicates in the upper end 30 of the radiator, a condenser comprising a base portion adapted to be removably secured in the said fill opening and forming a closure therefor, and a coil secured in said base with its attached end in communication with said 35 vapor space, the pitch of said coil being such that condensation will drain therefrom into said radiator, said coil comprising an open ended return section which communicates with the end of the coil proper remote from the base portion of the condenser, said return 40 section being reversely bent and extending through an opening in said base portion in register with the overflow pipe of the radiator.

45 2. In cooling apparatus for internal combustion engines embodying a radiator having a fill opening and a vapor space with which the condenser communicates in the upper end 50 of the radiator, a condenser comprising a base portion adapted to be removably secured in the fill opening and forming a closure therefor, and a coil secured in said base with its attached end in communication with said 55 vapor space, the pitch of said coil being such that condensation will drain therefrom into said radiator, said coil comprising an open ended return section which communicates with the end of the coil proper remote from the base portion of the condenser, said return 60 section being reversely bent and extending through an opening in said base portion in substantial register with the overflow pipe of the radiator and in such close proximity to the open end of said overflow pipe that the

latter will form practically a continuation of the return section of said coil.

3. In cooling apparatus for internal combustion engines embodying a radiator having a fill opening and a vapor space with which the condenser communicates in the upper end 70 of the radiator, a condenser comprising a base portion adapted to be removably secured in the fill opening to form a closure therefor, and a coil secured in said base with its attached end in communication with said vapor space, the pitch of said coil being such that condensation will drain therefrom into said radiator, said coil comprising an open ended 75 return section which communicates with the end of the coil proper remote from the base portion of the condenser, said return section extending through an opening in said base portion and being reversely bent to form a seal adapted to prevent vapors from entering 80 it from the said vapor space.

In testimony whereof I have signed my name to this specification on this 30th day of September, A. D. 1926.
